CLAIM

The ornamental design for food package, as shown and described.

DESCRIPTION

FIG. 1 is a front perspective view of the food package showing our new design;

FIG. 2 is a back view thereof;

FIG. 3 is a front view thereof;

FIG. 4 is a right side view thereof;

FIG. 5 is a left side view thereof;

FIG. 6 is a top view thereof; and

FIG. 7 is a bottom view thereof.

FIG. 8 is a front perspective view of another embodiment of the food package of our design;

FIG. 9 is a back view thereof;

FIG. 10 is a front view thereof;

FIG. 11 is a right side view thereof;

FIG. 12 is a left side view thereof;

FIG. 13 is a top view thereof; and

FIG. 14 is a bottom view thereof.

FIG. 15 is a front perspective view of another embodiment of the food package of our design;

FIG. 16 is a back view thereof;

FIG. 17 is a front view thereof;

FIG. 18 is a right side view thereof;

FIG. 19 is a left side view thereof;

FIG. 20 is a top view thereof; and

FIG. 21 is a bottom view thereof.

FIG. 22 is a front perspective view of another embodiment of the food package of our design;

FIG. 23 is a back view thereof;

FIG. 24 is a front view thereof;

FIG. 25 is a right side view thereof;

FIG. 26 is a left side view thereof;

FIG. 27 is a top view thereof; and,

FIG. 28 is a bottom view thereof.

The dash-dot-dot-break-away portions shown in FIGS. 8-12 and 22-26 are included to show that the food package has no specific length.

(Continued)

The broken line showing portions of the food package is included for the purpose of illustrating environmental structure and forms no part of the claimed design.
